UNITED STATES PATENT OFFICE.

JOHN M. CAGE, OF LONG BEACH, CALIFORNIA, ASSIGNOR TO CAGE ENGINE SYNDICATE, INC., OF NEW YORK, N. Y., A CORPORATION OF DELAWARE.

SIX-STROKE THREE-PHASE ENGINE.

1,367,797.

Specification of Letters Patent.

Patented Feb. 8, 1921.

Application filed June 16, 1914, Serial No. 845,367. Renewed March 20, 1919. Serial No. 283,897.

To all whom it may concern:

Be it known that I, JOHN M. CAGE, a citizen of the United States, residing at Long Beach, in the county of Los Angeles, 5 State of California, have invented new and useful Improvements in Six-Stroke Three-Phase Engines, of which the following is a specification.

This invention relates to an internal combustion engine in which the successive charges of gas are carried through six successive strokes from beginning to end of the complete cycle of the engine. My reasons for terming my engine a six-stroke 10 three phase engine will become clearly apparent from consideration of the following specification. I point out in this specification certain differences existing between my invention and the ordinary two-cycle type 15 of internal combustion engine, pointing out that there is full coöperation between the different mechanisms entering into the combination of my invention and distinctively showing the fact that my engine is not 20 merely a two-cycle engine with certain adjuncts.

The fundamental and primary features of an engine constructed in accordance with my invention may be briefly described as 25 follows: I provide three piston and cylinder mechanisms preferably directly connected in tandem so that the pistons reciprocate with each other. One of these piston and cylinder mechanisms is the charge 30 inspiring and compressing mechanism, drawing in a charge and compressing it on every two strokes, or on each complete reciprocation. Another of the piston and cylinder mechanisms is the work or power 35 mechanism, compressing and extending a charge upon every two strokes. The remaining mechanism is the exhaust suction and exhaust expulsion mechanism, drawing the exhaust from the work cylinder and 40 finally expelling it. The exhaust mechanism handles an exhaust charge every two strokes. Now the exhaust gases do not 45 pass directly from the work cylinder to the exhaust suction cylinder, but remain in an exhaust chamber for a certain period of time before going to the exhaust cylinder. This inactive period is one of the peculiar 50 features of my invention and is more fully explained hereinafter. Regardless of the

length of the inactive period, it will be 55 seen that the total action of my engine comprises six active strokes for each charge of gas passing through the engine; that is, each separate charge of gas is acted upon during six strokes of the engine. These six 60 strokes are performed by three different mechanisms, and each of these mechanisms passes through its complete cycle in two strokes; so that at any given time there are always three distinct charges of gas or 65 mixture in the engine, these three different charges being in different phases of the cycle of operation of the engine. For these reasons I call my engine a six-stroke three-phase engine; the number of strokes to complete the action on any one charge being 70 six and the number of different charges in the engine and being acted on by an active stroke at any one time being three. There are many additional features which I fully 75 explain in the following specification, including the arrangement of the ports in the work cylinder and the valve mechanism for operating the ports; the structure of the ports and passages forming interconnections between the various cylinders; the arrangement of the water jacket and the arrangement of the exhaust and compression chambers so as to distribute the heat 80 to keep as much thermal energy as possible 85 in the engine; and various other structural details and combinations which render the engine efficient in its action. The feature of the porting of the work cylinder is an important one. I arrange the exhaust and 90 intake ports each completely around the wall of the cylinder with the intake ports each completely above the exhaust ports. In the preferred construction, when the piston moves to the bottom of its stroke, it 95 uncovers the exhaust ports and the exhaust is drawn out by the vacuum produced by the previous action of the exhaust piston and cylinder; and after this has taken place, the inlet port is opened by a valve mechanism, preferably in the form of a sleeve 100 surrounding the work cylinder. The advantage of this construction lies primarily in cleaning the work cylinder completely of burned gases in the very short interval 105 while the exhaust ports are uncovered and then quickly charging the work cylinder with a complete fresh charge of mixture,

through the inlet ports which extend completely around the cylinder. The exhaust first passes out completely and the exhaust ports are closed just after the inlet ports 5 open; the times of opening and closing being such that the incoming fresh charge forces out the last portion of the burned gases without any of the fresh charge being lost.

10 I explain the transfer of heat from the exhaust gases to the fresh charges in the following detailed specification. It is one of the notable features of my invention that the exhaust gases finally expelled are very 15 cool, having left the greater part of their heat in the engine itself. It is also a notable feature that the cooling water carries off a comparatively small amount of heat. These facts are due to the construction here- 20 in explained whereby the heat of the exhaust gases is largely transferred to the incoming fresh charges after they are compressed.

I have shown the preferred forms of my 25 invention in the accompanying drawings, in which,

Figure 1 is a vertical cross section of my improved engine.

Fig. 2 is a vertical section taken in a 30 plane at an angle of forty-five degrees from the plan of the section of Fig. 1, as indicated by line 2—2 of Fig. 4.

Fig. 3 is a longitudinal vertical section showing a number of cylinders of my im- 35 proved engine,

Figs. 4, 5, 6, 7, 8, 9 and 10 are cross sections taken as indicated by the respective lines 4—4, 5—5, 6—6, 7—7, 8—8, 9—9 and 10—10 of Fig. 1,

40 Fig. 11 is a diagram illustrating graphically the strokes, cycles and phases of my improved engine.

I shall herein first describe the mechanical features of my engine and shall then 45 proceed to describe its operation and to particularly set forth the novel features thereof.

In the drawings the numeral 20 may 50 designate a crank case of suitable design with bearings 21 in which a crank shaft 22 is carried. The crank shaft has cranks 23 and eccentrics 24.

The eccentric corresponding to any one crank is placed at ninety degrees advance 55 ahead of its crank. This is clearly shown in Fig. 1 where the direction of rotation is indicated by the arrow and where the eccentric is shown with its center above the center of the crank shaft corresponding to the crank 23 which is shown to the left of the 60 crank shaft in that figure. Each of the eccentrics has its eccentric strap 25 and eccentric rod 26 connecting at 27 with the valve sleeve 28 corresponding to the pistons which are driven from the corresponding crank 65 23. Connecting rods 30 connect the various

crank pins with their respective pistons 31 which reciprocate in the several sleeves 28, the sleeves acting as cylinders to the pistons 31. The pistons 31 will be hereinafter referred to as the exhaust pistons. Piston 70 rods 32 extend upwardly from the exhaust pistons through compression heads 33 and through stuffing boxes 34 and connect with corresponding work pistons 35. Work pistons 35 reciprocate in work cylinders 36 in 75 the ordinary manner with sufficient clearance at the top of the stroke to provide for the desired compression of charge.

I shall now explain in detail the structure of the individual cylinders with their ports, 80 passages and chambers. Each complete cylinder comprises a lower and outer cylinder 40 and an upper and inner work cylinder which may generally be designated by the numeral 36. The outer cylinder 40 extends 85 from a point within the crank case upwardly to the flange 41 on the work cylinder 36; and this outer cylinder has a bore throughout its length, in which bore the sleeve 28 is adapted to reciprocate. The sleeve 28 is preferably ground to a working fit with the outer cylinder and is provided with packing rings 39 at intervals to prevent leakage around the sleeve, these packing rings being especially provided on opposite sides of the ports through the sleeve. (I hereinafter explain in detail the fitting and ring packing of the sleeve.) The upper work cylinder 36 has an extension sleeve 42 forming an integral part of the cylinder and 100 extending downwardly inside the valve sleeve 28 to a point just above the uppermost travel of the lower exhaust piston 31. Here the extension sleeve 42 carries the compression head 33, and this compression head 105 carries the stuffing box 34. The upper work piston 35 is slightly longer than the stroke of the piston, as shown in Fig. 1; and the inside of this work piston is hollowed out and the stuffing box 34 is made of such configuration as to practically fill the inner hollow of the piston 35 when the piston is at its lowermost point. By this means I obtain a light weight piston and yet obtain a small compression volume below the piston 35 115 when that piston is at its lowermost point. It will be understood that the stuffing box 34 is not exposed to the heat of combustion; it is kept comparatively cool by direct contact with fresh combustible mixture carrying the cool vapor of liquid fuel.

There are six sets of ports through the outer cylinder wall, and corresponding ports in the sleeve and the inner cylinder extension 42. Beginning with the uppermost, 125 these ports may be described as follows:—Somewhat above the lowermost position of the top of piston 35 the pressure inlet ports 50 are cut through the cylinder extension 42 and corresponding ports 51 and 52 are cut 130

through the sleeve 28 and through the inner wall 53 of the outer cylinder 40. The ports 52 communicate directly with an annular chamber 54 immediately surrounding the 5 inner wall 53 of cylinder 40 and inclosed within intermediate wall 55 of that cylinder. A plurality of intake passages 56 lead downwardly from this annular chamber 54 along the outside of the inner cylinder wall 53 and 10 these passages 56 connect at their lower ends with another annular chamber 57 which surrounds the inner cylinder wall 53 opposite compression ports 58 cut through the cylinder wall 53. Corresponding compression 15 ports 59 are cut through the inner cylinder extension sleeve 42; and corresponding ports 60 through the sleeve 28 serve these ports 58 and 59 and also serve the induction ports 61 and 62 which are cut through the cylinder 20 wall 53 and the extension sleeve 42, respectively, directly above the ports 58 and 59. It will be noted that compression ports 58 and 59 are cut with their lower edges flush with the upper surface of the compression 25 head 33; so that any liquid which may condense out of the mixture being compressed above the head cannot be held in the compression space below the piston but will pass outwardly through the ports 58 and 59. It 30 will be noted that the induction ports 61 and 62 connect with annular chamber 63, and that the compression passages 56 turn outwardly around this annular chamber 63 as shown at 56^a in Figs. 2, 7 and 8. The ports 35 61 and 62 are the original induction ports and the annular chamber 63 forms the original induction chamber or passage. This passage is connected to the intake opening 64 through which the combustible mixture is 40 originally inspired. The combustible mixture is drawn from any suitable source through the intake 64 and through the induction ports 61, 60 and 62 into the space below the piston 35 on the upward stroke of 45 that piston. The mixture is compressed and is driven out through the compression ports 59, 60 and 58 into the passage 57 and thence through the passages 56 and through the pressure inlet ports 52, 51 and 50 into the 50 work cylinder above the piston 35 at the appropriate time, as will be hereinafter explained.

The exhaust from above the work piston 55 passes out through ports 70, sleeve ports 71 and the port 72 into the exhaust chambers 73. These exhaust chambers 73 are preferably four separate chambers as is best shown in Fig. 5. These chambers might be described as enlarged passage ways leading 60 downwardly outside the middle wall 55 of the cylinder 40 and inside the outer wall 74 of this cylinder and connected at their lower ends with annular suction chamber 75 which surrounds the wall 53 of the outer cylinder 65 at a point somewhat below the compression

head 33. Suction ports 76 lead through the wall 53 at this point and these ports are adapted to be registered by sleeve ports 77, which ports 77 also serve ports 78 situated just above the ports 76 and just below the 70 compression head 33. These ports 78 connect with annular exhaust chamber 79, which is the final exhaust chamber, connecting through exhaust passage 80 to atmosphere or elsewhere. 75

In the different cross sections of Figs. 4 to 10 it will be noted that the exhaust passages or chambers 73 occupy a great deal of the space surrounding the inner wall 53 of the cylinder 40. The compression inlet passages 56 occupy four relatively small spaces, these passages being made of small capacity so that a high pressure may be maintained upon the gases therein. There are four water passages 85 which extend from the top 80 of the outer cylinder 40 downwardly to an annular water chamber 86 at the lower part of the cylinder. These water passages 85 are arranged between the exhaust passages or chambers 73 and are arranged directly adjacent the outside of the pressure inlet passages 56. This is clearly shown in Figs. 4, 5 and 6. Below the ports 72 and above the ports 61, and below and above the respective annular chambers corresponding to these 90 ports, the water passages 85 are extended completely around the cylinder as is shown at 85^a in Figs. 1 and 6. Where the passages 56^a turn outwardly to pass around the annular chamber 63 the water passages 85 are 100 divided each into two passages as is shown in Figs. 7 and 8. Below the annular chamber 57 the water passages are single as shown in Figs. 9 and 10. Immediately below the section shown in Fig. 10 all of the water 105 passages join the annular water chamber 86, as is shown in Fig. 2. This annular chamber has water inlet 87 as is best shown in Fig. 1.

The upper or work cylinder 36 has a water 110 jacket 90 completely surrounding it, this water jacket extending into the flange 41 and having openings or ports 92 which connect with the water passages 85 at their upper ends. The upper parts of the water 115 jackets 90 are provided with outlets 91 to which an ordinary water manifold may be attached.

I shall now explain the action of the sleeve with reference to the ports and pistons. In Fig. 1 the pistons are shown all on their up stroke and the sleeve is shown at the top of its stroke. Sleeve ports 77 are in full register with the final exhaust ports 78 and sleeve ports 60 are in full register with 120 initial induction ports 61 and 62. Sleeve ports 51 are in register with pressure intake ports 50 and 52 while sleeve ports 71 are above their positions of registration with exhaust ports 70 and 72. On the further up- 125

130

ward stroke of the pistons the sleeve will begin to move downwardly until, when the pistons are at the top of their strokes, the sleeve will be approximately half way down 5 its stroke and the ports 50 and 51 will be closed and ports 70 and 72 will be partially open, ports 61 and 62 will be closed as will also ports 78. Ports 59 and 58 and ports 76 will be just opening and will continue to 10 open during half of the downward stroke of the pistons and then will begin to close, closing when the pistons reach their lowermost positions and when the sleeve is in its position half way through its upward stroke. It 15 will be seen that the exhaust suction ports 76 will be open during the downward stroke of the pistons, as will also the compression ports 58 and 59. During the upward stroke of the pistons, the original induction ports 20 61 and 62 will be open and the final exhaust ports 78 will also be open. These four last mentioned sets of ports are controlled entirely by the sleeve; whereas the other two sets of ports are controlled by the sleeve in 25 conjunction with the piston 35. When the piston 35 reaches its lowermost position the sleeve ports 71 have already registered with and opened the exhaust ports 70 and 72; so that these exhaust ports are finally opened 30 by the upper end of the piston passing below them. At this time the sleeve is in its midway position traveling upwardly; and the sleeve inlet ports 51 are just out of registry with the pressure inlet ports 50 and 35 52. The sleeve traveling upwardly when the piston is at the bottom of its stroke begins to cut off the exhaust ports 70 and 72 and closes these exhaust ports before the piston on its upward stroke closes them. Just before the sleeve in its upward travel closes 40 the exhaust ports 70 and 72, its ports 51 begin to register with the inlet ports 50 and 52 and allow the compressed charge to pass from the passages 56 through these inlet 45 ports into the cylinder 36 above the piston. The pressure inlet opens before the piston has moved upwardly to the upper edges of the exhaust ports. Immediately after the inlet ports are opened the exhaust ports are 50 finally closed by the upward movement of the sleeve. The sleeve ports 51 continue to register with the inlet ports and these ports are finally cut off by the upward movement 55 of the piston 35. It will be noted that the exhaust ports are opened by the piston and closed by the sleeve, while the intake ports are opened by the sleeve and closed by the piston.

In the foregoing I have described my preferred form of engine and my preferred detailed construction. There are many minor features which may be varied, among which I may mention the means for driving the sleeve, the exact placements of the various 65 ports, and in fact all those features which

are not fundamentally required by the underlying principles of my invention to be precisely as described.

I wish to speak particularly of the fitting of the sleeve 28 and the placement of 70 packing rings 39. The sleeve is not made to fit so tightly that it will be pressure tight without the rings or other packing means. I have found it best practice in my engine to give the sleeve about ten thousandths of an 75 inch clearance at each contact surface; that is, the outer diameter of the sleeve is twenty-thousandths smaller than the bore of cylinder 40, and the same clearance is allowed on the inside of the sleeve where it fits around 80 the cylinder port 42. These figures may be varied; they are what I now consider good practice. I place a ring 39 at each side of each set of ports, as is clearly shown in Fig. 1. The exterior rings are set in the sleeve 85 itself while the interior rings are set in the cylinder port 42 and bear against the inner sleeve surface. With this construction, I prevent all leakage and at the same time make the sleeve to be easily moved. 90

The operation of my engine may be explained as follows: Consider that the pistons of any one unit are traveling upwardly in about the position shown in Fig. 1. As hereinbefore explained, the first induction ports 95 61 and 62 are open; and a fresh charge is drawn in through intake 64 into the space below the piston 35. At the top of the stroke the induction ports close and the compression ports 59 and 58 are then opened as 100 the piston starts down. The downward stroke of the piston then compresses the mixture beneath the piston out through the compression ports 58 and 59 into the compression passages 56. The piston reaches 105 the lower end of its stroke and starts upwardly again before the pressure inlet ports 50 and 52 are opened by the action of the sleeve. The compressed mixture then immediately rushes into the work cylinder 110 above the piston. On the subsequent upward stroke of the piston 35, this charge is compressed ready for ignition when the top of the stroke is reached. On the next downward stroke the gases are expanded; and 115 when the piston again reaches the bottom of its stroke the exhaust burned gases are drawn out into the exhaust passages or chambers 73, a partial vacuum having been generated in these exhaust passages by the 120 previous downward stroke of the lower piston 31. It will be noted that the exhaust gases do not pass immediately from the combustion chamber to the exhaust cylinder; but they remain in the exhaust passages during the next upward stroke of the pistons. During this upward stroke of the pistons the 125 gases are mechanically inactive; but an important thermal action takes place which I have hereinbefore mentioned and which I 130

shall hereinafter more fully explain. On the next downward stroke of the exhaust piston 31, the suction ports 76 are opened by action of the sleeve 28 and the exhaust gases 5 are drawn from the passages 73 into the exhaust cylinder. On the next upward stroke of the piston 31 these exhaust gases are expelled through exhaust passage 80, the ports 78 being opened by action of the sleeve ports 10 77. In ordinary practice, where the engine exhausts directly to atmosphere, the exhaust gases make a sharp explosive noise upon release into the atmosphere due to their sudden expansion. In my engine the exhaust 15 gases are merely pushed out into the air. There is no sharp explosive noise but only a gentle puff as the exhaust gases escape. When the engine is running at high speed there is a continuous whirring and humming 20 noise made by the exhaust. It might be here mentioned that this exhaust noise is the only noise made by the engine. It will be understood that, while I term the lower piston and cylinder mechanism an "exhaust expulsion 25 mechanism," its primary purpose may not at all times be the forcible expulsion of the exhaust. When the engine is operating normally against atmospheric pressure it is not necessary to force the exhaust to any great 30 extent out into the atmosphere. On the other hand, it is always a primary function of the "exhaust expulsion mechanism" to draw the exhaust gases from the exhaust chamber and to create a comparatively low 35 pressure in that chamber; in other words, it is always a function of this mechanism to draw the exhaust gases from the work cylinder, as herein explained, regardless of the subsequent forced expulsion.

40 I refer now more particularly to the diagram of Fig. 11. In this diagram I have shown diagrammatically several successive strokes of the pistons, up and down, and have numbered the successive strokes from 45 1 to 12. I have indicated the travel of the crank pin upwardly and downwardly by circumferential lines with arrows and have also indicated the travel of the corresponding valve eccentric by similar lines. The 50 diagram starts with the pistons in their lowermost positions traveling upwardly, stroke number one being the upward travel, stroke number two being the subsequent downward travel, and so on for any number of strokes.

55 Supposing that a charge "A" is drawn into the cylinder below the piston 35 by first upward stroke. This state of the charge I will designate by "A¹." The next stroke, number two, will compress this charge, and 60 this state is designated by "A²." The next upward stroke of the piston 35 will recompress the charge in the combustion chamber, indicated by "A³," and the next downward stroke is the expansion stroke indicated by 65 "A⁴." Now the next upward stroke of the

pistons is what I call the dead stroke, so far as this particular charge of gas is concerned. The next downward stroke of the pistons draws this charge "A" of gas into the exhaust cylinders, this state being indicated by "A⁵" and the last stroke upwardly forces this charge of gas out to atmosphere, being indicated by "A⁶." It will be noted that, due to the intervention of the dead stroke being the fifth stroke of the series, 70 it requires seven complete strokes of the engine to carry any one particular charge of gas through the complete cycle; but I will point out that there are always three charges of gas being acted upon by strokes 75 of the engine at any one particular time. Consider now the action of the piston 35 in drawing in and compressing the charges. After the charge "A" has been compressed on the downward stroke of this piston, the next 80 charge "B" will be drawn in on the succeeding upward stroke, as indicated by "B¹" in the diagram. This charge "B" will follow the charge "A" through the engine in the manner indicated, the dead stroke for 85 charge "B" being on the stroke numbered 7 simultaneous with the final expulsion stroke of charge "A." Similarly, charge "C" will be drawn in at the time of the second compression of charge "B" and this dead stroke 90 for charge "B" being on the stroke numbered 7 simultaneous with the final expulsion stroke of charge "A." Charge "C" will similarly be drawn in at the time of second compression of charge "C" and 95 follow that charge through the engine, and successive charges "B" and "C," etc., will follow in the same order. The total length of time, or number of strokes, during which any one particular charge is in the engine 100 is embraced by the brackets above the diagram. Consider the state of affairs at any time after the third charge of gas has been drawn into the engine—after the engine is in full operation; and, regardless of the dead strokes, it will be seen that there are always 105 three distinct charges of gas being acted upon by strokes of the engine. This is one of the things I wish to particularly dwell upon; and another important feature is that which I have previously spoken of, namely 110 that each charge of gas passes through six active strokes which succeed each other, none of which are simultaneous, but which do not necessarily succeed each other without an intermediate inactive stroke or strokes. 115

Consider now the state of affairs when one charge, say the charge "B" is in its dead stroke, standing in the exhaust passages 73. There are three other mechanically active charges of gas in the engine. The charge 120 "A" is being finally expelled the charge "C" is being compressed in the combustion chamber, and the charge "a" is being drawn in. The exhaust charge "B" is at relatively high temperature and during its stay in the 125 130

exhaust passages it imparts its heat to the water in water passages 85 and thence to the charge which is being compressed in the cylinder 36, (the water traveling upwardly 5 and carrying the heat with it), and it also imparts heat to the water and to the cylinder shell which is afterward radiated into the charge of gas under the piston 35. The total results of this radiation of heat from 10 the exhaust gases is that when the exhaust gases are drawn into the exhaust cylinder they are quite cool; so cool, in fact, that the hand can be held in the exhaust which comes finally from the exhaust passage 80. The 15 cooling water does not carry away any large portion of this heat, giving it up to the incoming charges; and the net result is that high thermal efficiency is attained by keeping the heat in the engine and applying it 20 to the succeeding charges of gas at proper times. The incoming charge of fresh mixture is cool and it is not until it is compressed that it begins to receive any great amount of heat from the exhaust gases and 25 from the combustion above the piston 35. This addition of heat tends to raise the pressure of compression, which is a very desirable feature as it aids the compressed gases in quickly moving into the combustion cylinder. The actual volume of mixture entering 30 the combustion cylinder is larger than the actual volume drawn in under piston 35, due to this accession of heat. As hereinbefore explained, the compressed charge stands 35 in the relatively small space under the piston 35 and in the small compression passages 56 when the piston is at the bottom of its stroke. The partial vacuum generated in the exhaust passages 73 by the previous stroke 40 of the exhaust piston 31 draws the exhaust gases out of the combustion chamber until the pressures are equalized. The inlet ports 50 and 52 open just before the exhaust ports close, so that the inrushing charge under 45 pressure will remove the remaining exhaust gases before the exhaust ports close. The remainder of the fresh charge then enters the combustion cylinders ready for the next compression stroke.

50 Having described a preferred form of my invention, I claim:

1. The combination of a two stroke compression mechanism adapted to draw in and compress a charge of gas on every two 55 strokes, a two stroke work mechanism adapted to compress and expand a charge on every two strokes, an exhaust chamber, a two stroke exhaust mechanism adapted to draw in and expel an expanded charge 60 every two strokes, the suction stroke of said exhaust mechanism being simultaneous with the work stroke of the work mechanism, and a single valve mechanism positively operated from the work mechanism for conveying 65 a charge successively to and from said

mechanisms and said chamber in the order named so that a single charge is acted on successively by the six strokes of the three mechanisms, and so that the charge after expansion in the work mechanism remains 70 in said exhaust chamber during at least one stroke of the exhaust mechanism.

2. The combination of a two stroke compression mechanism of the piston and cylinder type, a two stroke work mechanism of the piston and cylinder type, an exhaust chamber, a two stroke exhaust mechanism of the piston and cylinder type, the suction stroke of said exhaust mechanism being simultaneous with the work stroke of the 80 work mechanism, all the said mechanisms being interconnected so that their strokes are synchronous, and a single valve means positively operated in coöperation with said mechanisms to cause the inspiration of a 85 gaseous charge to the compression mechanism on a first stroke, the compression of said charge on the next stroke of said mechanism, the transfer of said compressed charge to the work mechanism and compression 90 therein on the next succeeding stroke, expansion of said charge in the work mechanism on the next succeeding stroke, transfer of said charge to and holding in the exhaust chamber during at least one stroke of 95 the exhaust mechanism, inspiration by the exhaust mechanism of the charge from said chamber on a successive stroke, and expulsion of the charge on the next succeeding stroke.

3. The combination of a compression mechanism, a work mechanism and an exhaust expulsion mechanism all contained within a single casing, passages within said casing through which a compressed charge 105 may pass from the compression mechanism to the work mechanism, passages in said casing into which the exhaust gases from the work mechanism may pass and from which said exhaust gases may pass to the 110 exhaust expulsion mechanism, and a single valve means positively operated in coöperation with said mechanisms for causing a charge of gas to pass through said mechanisms in order named and to cause the 115 charge to be held in said exhaust passages for an interval before passing to the exhaust expulsion mechanism.

4. The combination of a charge compression mechanism including a cylinder and piston, a work mechanism including a cylinder and piston, and an exhaust expulsion mechanism including a cylinder and piston all contained within a single casing, passages within said casing leading from the 125 compression mechanism to the work mechanism, exhaust passages within said casing leading from the work mechanism to the exhaust expulsion mechanism, said exhaust passages being adjacent said first mentioned 130

passages, and valve means to cause the transfer of a gaseous charge through said mechanisms in the order named and to cause the stay of the charge in said exhaust passages throughout at least one stroke of the piston of the exhaust expulsion mechanism.

5. The combination of a cylindrical casing having therein a work piston and an exhaust piston interconnected and adapted to 10 reciprocate together, a cylinder head above the work piston and another cylinder head between the two pistons forming a work space above the work piston, a compression space below the work piston and an exhaust 15 space above the exhaust piston, compression passages between the compression space and the work space arranged in said cylindrical casing, exhaust passages between the work space and the exhaust space arranged 20 within the cylindrical casing adjacent said compression passages, and valve means to cause the transfer of a gaseous charge to and from said compression space and thence through said compression passages to said 25 work space and thence into said exhaust passages and thence to said exhaust space, the charge being held in the exhaust passages during at least one stroke of the exhaust expulsion piston.

30. 6. The combination of a cylindrical casing having therein a work piston and an exhaust piston interconnected and adapted to reciprocate together, a cylinder head above the work piston and another cylinder 35 head between the two pistons, forming a work space above the work piston, a compression space below the work piston and an exhaust space above the exhaust piston, compression 40 passages between the compression space and the work space arranged in said cylindrical casing, exhaust passages between the work space and the exhaust space arranged within the cylindrical casing adjacent said compression passages, and valve 45 means including a ported sleeve within said casing and surrounding said piston to cause the transfer of a gaseous charge to and from said compression space and thence through said compression passages to said work 50 space and thence into said exhaust passages and thence to said exhaust space, the charge being held in the exhaust passages during at least one stroke of the exhaust piston.

55. 7. The combination of a cylindrical casing having therein a work piston and an exhaust piston interconnected and adapted to reciprocate together, a cylinder head above the work piston and another cylinder head between the two pistons forming a work 60 space above the work piston, a compression space below the work piston and an exhaust space above the exhaust piston, compression 65 passages between the compression space and the work space arranged in said cylindrical casing, exhaust passages between the work

space and the exhaust space arranged within the cylindrical casing adjacent said compression passages, there being ports through the cylindrical casing arranged in sets completely around the cylindrical casing to communicate with the compression space, the work space and the exhaust space, respectively, and valve means including a valve sleeve having corresponding ports there-through extending in sets completely around the sleeve and adapted to register with the various casing ports to cause the transfer of a gaseous charge to and from said compression space and thence through said compression passages to said work space and thence 70 into said exhaust passages and thence to said exhaust space, the charge being held in the exhaust passages during at least one stroke of the exhaust piston.

8. In an engine of the character described, 85 a work cylinder and a piston therein, intake ports extending through the walls of the work cylinder and completely around the work cylinder at a point above the lowermost point of piston travel, exhaust ports extending through the walls of the work cylinder and completely around the cylinder above the point of lowermost piston travel, the intake and exhaust ports being arranged one above the other, means for maintaining a 90 partial vacuum at said exhaust ports, and a single valve means embodying a sleeve co-operating with the piston and controlling both the intake and exhaust ports.

9. In an engine of the character described, 100 a work cylinder and a piston therein, intake ports extending through the walls of the work cylinder and completely around the work cylinder at a point above the lowermost point of piston travel, exhaust ports 105 extending through the walls of the work cylinder and completely around the cylinder above the point of lowermost piston travel, the intake and exhaust ports being arranged one above the other, means for providing 110 a gaseous charge under pressure at said intake ports, means for maintaining a partial vacuum at said exhaust ports, and a single valve means embodying a sleeve co-operating with the piston and controlling both the intake and exhaust ports.

10. The combination of a charge compression mechanism, a work mechanism and an exhaust expulsion mechanism all contained within a single casing, passages within said 120 casing leading from the compression mechanism to the work mechanism and through which a compressed charge may pass from the compression mechanism to the work mechanism, passages in said casing adjacent said compression passages leading from the work mechanism to the exhaust expulsion mechanism and through which exhaust gases may pass from the work mechanism to the 125 exhaust expulsion mechanism, a single valve 130

means positively operated in coöperation with said mechanisms for causing a charge of gas to pass through said mechanisms in the order named and to cause the charge to be held in said exhaust passage for an interval before passing to the exhaust expulsion mechanism, and water circulation spaces in said casing adjacent both said passages.

11. The combination of a cylindrical casing having therein a work piston and an exhaust piston interconnected and adapted to reciprocate together, a cylinder head above the work piston and another cylinder head between the two pistons forming a work space above the work piston, a compression space below the work piston and an exhaust space above the exhaust piston, compression passages between the compression space and the work space arranged in said cylindrical casing, exhaust passages between the work space and the exhaust space arranged within the cylindrical casing adjacent said compression passages, valve means to cause the transfer of a gaseous charge to and from said compression space and thence through said compression passages to said work space and thence into said exhaust passages and hence to said exhaust space, the charge being held in the exhaust passages during at least one stroke of the exhaust expulsion piston, and water circulation spaces in said casing adjacent both the compression passages and the exhaust passages.

12. The combination of a cylindrical casing having therein a work piston and an exhaust piston interconnected and adapted to reciprocate together, a cylinder head above the work piston and another cylinder head between the two pistons forming a work space above the work piston, a compression space below the work piston and an exhaust space above the exhaust piston, compression passages between the compression space and the work space arranged in said cylindrical casing, exhaust passages between the work space and the exhaust space arranged within the cylindrical casing adjacent said compression passages, there being ports through the cylindrical casing arranged in sets completely around the cylindrical casing to communicate with the compression space, the work space and the exhaust space, respectively, valve means including a valve sleeve having corresponding ports therethrough extending in sets completely around the sleeve and adapted to register with the various casing ports to cause the transfer of a gaseous charge to and from said compression space and thence through said compression passages to said work space and thence into said exhaust passages and thence to said exhaust space, the charge being held in the exhaust passages during at least one stroke of the exhaust piston, and water circulation passages in said casing

adjacent both the exhaust passages and the compression passages.

13. In an engine of the character described, a cylindrical casing and a piston therein, said cylindrical casing embodying an inner and an outer wall with an annular space between, annular chambers formed in said casing and extending completely around the casing at points below and above the piston, ports extending through the inner wall of said casing and communicating with said annular chambers, passages formed in said casing, in the space between its inner and outer walls, connecting the annular chambers together, there also being a water circulation space between the inner and outer walls of said casing adjacent said passages.

14. In an engine of the character described, a cylindrical casing and a piston therein, said casing including an inner and outer wall with an annular space between them, two sets of ports through the inner wall of the casing below the piston and two sets of ports through the inner wall of the casing above the piston, each set of ports extending completely around the cylinder casing, annular chambers contained within said casing, one chamber for each set of ports and communicating therewith, intake means in connection with one of the annular chambers below the piston, compression passages formed between the inner and outer walls of said casing leading from the other of said annular chambers below the piston to one of said annular chambers above the piston, exhaust passages formed between the inner and outer walls of said casing and in communication with the other of said annular chambers above the piston, and water circulation passages occupying the remaining space between said inner and outer casing walls, the arrangement being such that water circulating through said space is adjacent both the compression and exhaust passages.

15. The combination of a cylindrical casing having therein a work piston and an exhaust piston connected together and adapted to reciprocate together, said cylindrical casing including an inner and an outer wall with an annular space between, a cylinder head above the work piston and another cylinder head between the two pistons forming a work space above the work piston, a compression space below the work piston and an exhaust space above the exhaust piston, two sets of ports leading through the inner casing wall below the work piston, above the work piston and above the exhaust piston respectively, each set of said ports extending completely around the cylindrical casing, annular chambers formed within said cylindrical casing one in direct communication with each of said sets of ports,

- 5 said annular chambers extending completely around said cylindrical casing, induction means connecting with one of said annular chambers below said work piston, compression 5 passages formed between the inner and outer casing walls leading from the other of said annular chambers below said work piston to one of the annular chambers above said work piston, exhaust passages formed between 10 said inner and outer casing walls adjacent said compression passages leading from the other of said annular chambers above said work piston downwardly to one of the annular chambers above said exhaust piston, 15 an outlet means connecting with the other of said chambers above said exhaust piston, water circulation spaces between said casing walls adjacent both said passages, and valve means coöperating with said pistons 20 having ports adapted to register with said casing ports.
16. The combination of a cylindrical casing having therein a work piston and an exhaust piston connected together and adapted to reciprocate together, said cylindrical casing including an inner and an outer wall with an annular space between, a cylinder head above the work piston and another cylinder head between the two pistons forming a work space above the work piston, a compression space below the work piston and an exhaust space above the exhaust piston, compression 25 passages between the compression space and the work space arranged in said cylindrical casing, exhaust passages between the work space and the exhaust space arranged within the cylindrical casing adjacent said compression passages, and valve means to cause the transfer of a gaseous charge to and from said compression space and thence through said compression passages to said work 30 space and thence into said exhaust passages and thence to said exhaust space, said valve means embodying a ported sleeve coöperating with said pistons.
18. In an internal combustion engine, the combination of a work mechanism having a work stroke, coöperating exhaust expulsion mechanism having a suction stroke simultaneous with the work stroke of the work mechanism, an exhaust chamber communicable with both mechanisms, and a valve mechanism controlling communication of the chamber with said mechanisms opening communication with the work mechanism at the end of its work stroke and opening communication with the expulsion mechanism during its suction stroke, the second mentioned communication being always closed while the first mentioned communication is open, thereby preventing direct passage of 35 exhaust gases from the work mechanism through said chamber to the expulsion mechanism.
19. In an internal combustion engine, the combination of a work mechanism having a work stroke, coöperating exhaust expulsion mechanism having a suction stroke simultaneous with the work stroke of the work mechanism, an exhaust chamber communicable with both mechanisms, and a single positively operated valve mechanism controlling communication of the chamber with said mechanisms opening communication with the work mechanism at the end of its work stroke and opening communication 40 with the expulsion mechanism during its suction stroke, the second mentioned communication being always closed while the first mentioned communication is open, thereby preventing direct passage of 45 exhaust gases from the work mechanism through said chamber to the expulsion mechanism.
20. In an internal combustion engine, the combination of a work mechanism having a work stroke, a coöperating exhaust expulsion mechanism having a suction stroke simultaneous with the work stroke of the work mechanism, an exhaust chamber communicable with both mechanisms, and a 50 valve sleeve surrounding the pistons within said cylindrical casing having ports adapted to register with said casing ports.
17. The combination of a cylindrical casing having therein a work piston and an exhaust piston interconnected and adapted 55

- valve mechanism controlling communication of the chamber with said mechanisms to open communication with the exhaust mechanism during its suction stroke and close 5 that communication near the end of that stroke and to open communication with the work mechanism at the end of its work stroke after closure of communication with the exhaust mechanism.
- 10 21. In an internal combustion engine, the combination of a work mechanism having a work stroke, a coöperating exhaust expulsion mechanism having a suction stroke simultaneous with the work stroke of the 15 work mechanism, an exhaust chamber communicable with both mechanisms, and a single positively operated valve mechanism controlling communication of the chamber with said mechanisms to open communication 20 with the exhaust mechanism during its suction stroke and close that communication near that end of that stroke and to open communication with the work mechanism at the end of its work stroke after closure 25 of communication with the exhaust mechanism.
22. In an internal combustion engine, the combination of a single cylindrical casing, a work piston and a coöperating exhaust 30 expulsion piston therein, heads forming work and expulsion chambers in said casing adjacent said pistons, an exhaust chamber communicable with the work and expulsion 35 chambers, and a valve mechanism embodying a sleeve valve controlling communication of the exhaust chamber with both the work and expulsion chambers, and means to move said sleeve valve coöperatively with the pistons, so that communication with the 40 two said chambers is not simultaneous.
23. In an internal combustion engine, the combination of a single cylindrical casing, a work piston and an exhaust expulsion piston therein and connected to reciprocate together, heads forming work and exhaust 45 expulsion spaces on corresponding sides of the work and expulsion pistons, respectively, so that the work piston may have a work stroke and the expulsion piston a simultaneous suction stroke, an exhaust chamber communicable with both the work and exhaust expulsion spaces, a sleeve valve controlling communication of said chamber with both spaces, and means to move said 55 valve coöperatively with the piston so that communication is established with the exhaust expulsion space during the suction stroke of its piston and cut off near the end of that stroke and so that communication with the work space is established at the 60 end of the work stroke after communication with the exhaust expulsion space is cut off.
24. In an internal combustion engine, the combination of a work mechanism having a work stroke, a coöperating exhaust mechanism having a suction stroke, an exhaust chamber, and valve mechanism for communicating the work mechanism with the chamber at the end of the work stroke, for holding the charge in the chamber during at least one stroke of the mechanisms, and for then communicating the chamber with the exhaust mechanism during its suction stroke. 95
25. In an internal combustion engine, the combination of a work mechanism having a work stroke, a coöperating exhaust mechanism having a suction stroke, an exhaust chamber, and valve mechanism positively operated in coöperation with the work and exhaust mechanisms for communicating the work mechanism with the chamber at the end of the work stroke, for holding the charge in the chamber during at least one stroke of the mechanisms, and for then communicating the chamber with the exhaust mechanism during its suction stroke. 75
26. In an engine of the character described, a cylindrical casing and a piston in the lower part thereof, a sleeve valve within the casing and in which the piston reciprocates, a head at the upper end of the cylindrical casing, a cylinder sleeve depending from said head; a piston working in said cylinder sleeve and connected to said first mentioned piston, and an intermediate head 90 carried by said cylinder sleeve between the two pistons. 95
27. In an engine, the combination of a cylinder structure, a movable sleeve, a pair of pistons reciprocable within the sleeve, means effecting coöperative movement of the pistons and sleeve, a head between the pistons, and means to support the head embodying a sleeve within the movable sleeve connected at one end with the cylinder structure. 100
28. In an engine, the combination of a movable sleeve, a pair of pistons within the sleeve, means for effecting coöperative movement of the pistons and sleeve, a head between the pistons, and means to support the head embodying a sleeve within the movable sleeve. 110
29. In an internal combustion engine, the combination of a work mechanism, an exhaust chamber into which the mechanism exhausts, valve means coöperating with the work mechanism to hold the exhaust in the exhaust chamber during a stroke of the work mechanism, and means for cooling the exhaust while in the exhaust chamber. 115
30. In an internal combustion engine, the combination of a work mechanism, a charge compressing mechanism, an exhaust chamber into which the work mechanism exhausts, valve means coöperating with the work mechanism to hold the exhaust in the exhaust chamber during a stroke of the work mechanism, and means for transferring heat 120
- 125

from the exhaust to the charge which is compressed by the compressing mechanism, to cool the exhaust in the chamber and heat the charge.

- 5 31. In an engine, the combination of a cylinder structure, a movable sleeve therein, a piston movable within the sleeve, means for effecting coöperative movement of the piston and sleeve, the cylinder structure embodying a head at one end of the sleeve, another head in the sleeve at the other side of the piston, and means to support the last mentioned head embodying a sleeve extending within the movable sleeve.
- 10 32. In an engine, the combination of a cylinder structure, a movable sleeve therein, a piston movable within the sleeve, means for effecting coöperative movement of the piston and sleeve, the cylinder structure embodying a head at one end of the sleeve, another head in the sleeve at the other side of the piston, and means to support the last mentioned head embodying a sleeve extending within the movable sleeve and supported 25 at one end on the head end of the cylinder structure.

33. In an engine, a cylinder structure, a piston therein, a movable sleeve within which the piston reciprocates, a head at the 30 upper end of the cylinder structure, a cylinder sleeve depending from said head to a point below said piston and forming the working cylinder for said piston, and a head supported by the depending sleeve at its 35 lower end below the piston.

34. In an engine, the combination of a cylinder structure, a movable sleeve therein, a head at one end of the cylinder, two pistons within the sleeve, means for effecting 40 coöperative movement of the sleeve and pistons, and a head within the sleeve between the pistons, said heads forming with the pistons three working chambers.

35. In an internal combustion engine, the 45 combination of a cylinder structure, a movable sleeve therein, a piston reciprocable within the sleeve, means for effecting coöperative movement of the sleeve and piston, a head at one end of the sleeve forming with 50 one end of the piston an explosion chamber, a head within the sleeve at the other side of the piston forming with the other end of the piston a charge compression chamber, there being exhaust and intake ports for the 55 explosion chamber and the compression chamber, and a communicating passage between the exhaust port of the compression chamber and the intake port of the explosion chamber, in the cylinder structure, the sleeve having ports and constituting valve means for controlling transfer of charge from the compression space to the explosion space.

the exhaust port of the compression chamber and the intake port of the explosion chamber, in the cylinder structure, the sleeve having ports and constituting valve means 60 for controlling the intake and discharge of charge to and from the compression chamber and the intake of charge to the explosion chamber.

36. In an internal combustion engine, the 65 combination of a cylinder structure, a movable sleeve therein, a piston reciprocable within the sleeve, means for effecting coöperative movement of the sleeve and piston, a head at one end of the sleeve forming with 70 one end of the piston an explosion chamber, a head within the sleeve at the other side of the piston forming with the other end of the piston a charge compression chamber, there being exhaust and intake ports for the 75 explosion chamber and the compression chamber, and a communicating passage between the exhaust port of the compression chamber and the intake port of the explosion chamber, in the cylinder structure, the 80 sleeve having ports corresponding to each of the cylinder structure ports and constituting valve means for controlling all of said ports.

37. In an internal combustion engine, the 85 combination of a cylinder structure, a movable sleeve therein, a piston reciprocable within the sleeve, means for effecting coöperative movement of the sleeve and piston, a head at one end of the sleeve forming with 90 one end of the piston an explosion chamber, a head within the sleeve at the other side of the piston forming with the other end of the piston a charge compression chamber, there being exhaust and intake ports for the 95 explosion chamber and the compression chamber, and a communicating passage between the exhaust port of the compression chamber and the intake port of the explosion chamber, in the cylinder structure, the 100 sleeve having ports and constituting valve means for controlling transfer of charge from the compression space to the explosion space.

In witness that I claim the foregoing I 105 have hereunto subscribed my name this 11th day of June, 1914.

JOHN M. CAGE.
